UNITED STATES PATENT OFFICE.

GEORGE H. SHAW, OF LOS ANGELES, CALIFORNIA.

MILK-CAN-IDENTIFYING MEANS.

Application filed February 5, 1921. Serial No. 442,707.

To all whom it may concern:

Be it known that I, GEORGE H. SHAW, a citizen of the United States, residing at Los Angeles, in the county of Los Angeles and State of California, have invented a new and useful Improvement in Milk-Can-Identifying Means, of which the following is a specification.

At present milk cans require to be billed from the dairy to the dealer and from the dealer to the dairy and so far as known they are always tagged with a tag of shipping directions which is tied onto the handle of the can, or by a card inserted into a pocket attached to the can. These tags and cans are expensive and are likely to be torn off or knocked out of the pocket or to be damaged by the weather, and because of the somewhat permanent character of the tag when tied to the can, they become unsanitary and a menace to health, and an object of the present invention is to provide a cheap and simple contrivance more convenient and desirable than such tags or cards, and to provide for ready removal and resupply of the shipping directions.

In the present invention I mark the can by a simple slip of thin paper that will always be removable in the operation of washing the can before refilling, and which can be replaced at practically no expense.

A further object of the invention is to provide a permanent home address in the holder which may be exposed when the container reaches its shipping destination.

Another object of the invention is to provide a simple and cheap construction in which drainage for the holder is made certain, so as to prevent accumulation of moisture around the edges of the address slip, which would be likely to soften it so as to make it fall out.

My device comprises a holder adapted to conform to the curvature of the can and to be placed in some protected position thereon, preferably near the top on what is known as the "breast" of the can. The holder is preferably formed from a blank of sheet metal having its edges so cut that when they are bent up they will form guideways or pockets on the sides and bottom to receive and retain by its edges, a thin slip of paper, and an overhanging ledge spaced from the upper ends of the side guideways to prevent the card from slipping out. The device is also provided with vents between the

side and bottom guide members to afford drainage. The device has also a rear wall on which may be painted or stamped the home address of the can and by which it may be attached by solder or in other suitable manner to the can.

Other objects, advantages and features of invention may appear from the accompanying drawing, the subjoined detail description and the appended claims.

The accompanying drawing illustrates the invention.

Figure 1 is a perspective view showing the paper slip holder on a milk can.

Fig. 2 is a view of a stamping from which the holder may be bent up. Dotted lines indicate the line of the bends.

Fig. 3 is a face view of the holder in place on the can, a fragment of which is shown.

Fig. 4 is a section on line x^4 , Fig. 3.

Fig. 5 is a horizontal section on line x^5 , Figs. 3 and 4.

In Figs. 1, 3, 4 and 5 the paper slip is shown inserted.

Fig. 6 is a perspective view of the holder detached.

Fig. 7 is an enlarged fragmental view in section on line x^7 , Fig. 6.

The paper slip retainer consists of a plate 1 of metal conformed to the can 2 and having ledges 3, 4, 5 and 6 at the bottom, ends and top; the bottom ledge 3 and the end ledges 4, 5 forming with the body of the plate, grooves 7 to receive a paper identification slip 8. The ledges are formed by bending over the several ears indicated at 3', 4', 5', in the stamping shown in Fig. 2.

These ears are bent over into practical parallelism with the main body and brought close thereto so as to form the channels 7, and are adapted to conveniently accommodate the three edges of a slip of paper.

The ledge 6 extends out beyond the surface of the body practically to the same distance as the ledges 3, 4, 5 and serves to prevent the paper slip from being withdrawn edge-wise from the channels 7 formed in front of the body. Said ledge 6 is spaced from the end ledges 4, 5 and thereby permits easy insertion and withdrawal of the slip 8, and at the same time, by extending out beyond the surface of the body such ledge prevents accidental displacement of the slip 8.

In practice, to construct the retainer, a blank A is clipped at the lower corners as indicated at 9, and the ears 3', 4' and 5' thus

appearing are preferably bent up so as to leave drainage outlets 10 at the corners.

The sight opening 11, between the ledges, is preferably of sufficient size to allow the identifying name 12 to be seen.

The slip of paper 8 may be of any convenient character, the purpose being to allow the shipper to use any paper available even a piece of the blank margin of a newspaper, or a blank scrap of wrapping paper or a piece of letter paper or in fact any piece of paper or the like, large enough to occupy the space between the channels and not too thick to be inserted into the channels.

15 An advantage in providing a holder for a slip of paper as distinguished from a holder for a name card, is that in the operation of washing the cans the can washer by putting his wet thumb on the addressed slip 20 can easily remove the slip so that the can may be thoroughly cleansed.

Preferrably the paper slip retainer is placed between the rigid supports 14 of the handle 15 thus to protect the slip from contact of bodies which might rub the paper slip and crumple it so as to withdraw it 25 from the retainer.

In practice the paper slip retainers will be made with appropriate curvature to conform to the place on the can to which it is desired to be fastened, and the detached retainers may be delivered to the market and may be soldered onto the cans.

In constructing the paper slip holder a 35 flat piece of sheet iron, for instance, a piece of No. 24 galvanized sheet iron is cut in the shape shown in Fig. 2. The two side edges and the bottom edge are then turned back. Then the top edge is slightly turned over. 40 After this operation the piece of sheet iron is put into a can straightener and one trip of the hammer will give it the slightly curved form to fit the surface of the can.

Where it is desired, the plate may be 45 provided as shown in Fig. 6 with a permanent name and address 16 to indicate the owner and home address of the can. This is covered over by the paper slip when such slip is inserted into the retainer and when 50 the can is destined to its home address the

paper slip will be removed so as to expose the permanent address. When it is desired to change the can to another address, a new paper slip with another address on it will be inserted. By removing the slip the can 55 visibly bears the address to which it is to be returned.

I claim:

1. Milk can identifying means comprising a plate of metal having return shipping directions stamped thereon and being conformed to the curvature of the can to which it is applied and having ledges at its bottom, ends and top; the bottom and end ledges forming grooves to receive an identification slip having shipping directions thereon, and said ledges being spaced apart to form an open-sight space and to form drainage outlets at the corners; the top ledge being adapted to prevent accidental removal of the identification slip, and being spaced from the end ledges to allow the identification slip to be inserted to give shipping directions and to obscure the return shipping directions and to be removed to expose the return shipping directions.

2. Milk can identifying means comprising a plate of metal having return shipping directions thereon and being conformed to the curvature of the can to which it is applied and having ledges at its bottom, ends and top; the bottom and end ledges forming grooves to receive an identification slip having shipping directions thereon and said ledges being spaced apart to form an open-sight space and to form drainage outlets at the corners; the top ledge being adapted to prevent accidental removal of the identification slip, and being spaced from the end ledges to allow the identification slip to be inserted to give shipping directions and to obscure the return shipping directions and to be removed to expose the return shipping directions.

In testimony whereof, I have hereunto set 95 my hand at Los Angeles, California, this 28th day of January, 1921.

GEORGE H. SHAW.
